WATER HEATER

Filed June 13, 1927

UNITED STATES PATENT OFFICE

THOMAS A. RONSTROM, OF CHICAGO, ILLINOIS

WATER HEATER

Application filed June 13, 1927. Serial No. 198,565.

My invention relates to an improvement in water heaters and has particular reference to an improved storage water heater for use in household and other locations where it is desirable to connect the water system 5 with a source of hot water supply.

The primary object of my invention is to provide a storage heater having a maximum area of heating surface.

10 A further object of my invention is to provide a heater of the class described in which the products of combustion from the burner with which the heater is equipped will be brought in intimate contact with the heating surface during its entire passage 15 through the heater, so that the greatest possible percentage of the heat generated in the combustion chamber may be transferred to the water within the tank.

20 A still further object of the invention is to provide a heater which will be unusually durable in use, which will not require repairs and which will give entire satisfaction over a long period.

25 A still further object of my invention is to so construct a heater that condensation is practically eliminated or at least reduced to such an extent that the disadvantages of the same are of no consequence.

30 With these and further objects in view I will now proceed to describe the preferred embodiment of my invention with reference to the accompanying drawings, in which—

35 Fig. 1 is a vertical section of the heater assembly;

40 Fig. 2 is a horizontal section through the heating drum or disk, as it is sometimes called, the section being taken on the line 2—2 Fig. 3;

45 Fig. 3 is a vertical section through the heating drum or disk, the section being taken on the line 3—3 Fig. 2;

50 Fig. 4 is a cross section through the hot water circulating connection, the section being taken on the line 4—4 Fig. 1;

55 Fig. 5 is a detail view in side elevation of one of the sections which make up the hot water circulating connection;

60 Fig. 6 is a vertical section of one of the sections shown in Fig. 5;

Fig. 7 is another vertical section of one of the sections shown in Fig. 5, showing a modified form, and

Fig. 8 is a vertical section of the form shown in Fig. 7 taken on a different side. 55

Referring now to the drawings in detail—5 represents the tank or boiler, as the case may be, the same being made as is customary with heaters of this type but, of course, modified in several particulars to accommodate the 60 assembly of the invention. The tank is equipped with a dome-shaped bottom 6 having skirted sides 7 connected to the dome 6 by rivets, bolts or the like 8, which are employed for securing the flanged side 9 of the dome 6 to the upper edge 10 of the skirt 7. The edge 10 in this connection is made with a diameter smaller than the skirt 7, so as to accommodate the thickness of the flange 9. The side wall of the tank 5 extends down 70 over the skirt 7 and the lower edge thereof is reinforced by a band or ring 11 so as to make a rigid mounting for the legs 12.

The top of the tank 5 is made with a dome-shaped cover 13 which is secured by 75 rivets 14 to the side wall.

Housed within the skirt 7 below the dome 6 is a heating drum 15 or disk, as it is sometimes called, and for convenience I will refer to the same as a heating drum. 80

The drum will ordinarily be of casting having a convex bottom 16 and a modified conical top 17. Connected centrally of the modified conical top 17 is a hot water circulating connection 18 the same suspending 85 the top below the dome-shaped bottom 6.

Communicating with the bottom of the tank 5 is a cold water connection 19, the same comprising a short length of pipe projecting into the side of the tank through an opening 20 with the fitting 21 on the outside of the tank connected to the connection 19 at one end and with a threaded nipple 22 at the opposite end. The nipple 22 is threaded into the side of the drum 15, so that the water in the tank may circulate into the drum to be heated thereby. Any suitable fitting will be satisfactory for this cold water connection so long as the same is water tight and will supply the necessary 90 95 100

volume of water and providing that it may be easily taken apart for cleaning purposes if desired. The fitting will also serve to support the drum 15 in conjunction with 5 the hot water circulating connection 18.

For the opening 20 into the side of the tank, I ordinarily use a flange bushing 23 with internal threads for the reception of the threaded nipple 24. The flange of the 10 bushing may be riveted to the side of the tank, as shown.

The construction of the drum 15 is of considerable importance and I have found 15 that to give a maximum efficiency it is best to make the same with an annular internal baffle-like wall 25 disposed concentrically of the drum so that the water entering the drum through the nipple 22 of the fitting 20 will be deflected in opposite directions around the baffle 25. As a matter of fact 25 the part 25 is more than a baffle. It is in reality a vertical annular wall which extends from top to bottom of the drum and internally divides the same into two communicating water compartments, the outer compartment directly communicating with the intake in the side of the drum and the inner compartment directly communicating 30 with the water outlet in the drum.

30 The opposite side of the baffle from that of the water intake is open and opposite this opening is a deflector 26 to direct the water into the area defined by the baffle 25, and in this way water entering the drum 35 will be divided into two separate streams and circulated throughout the outer compartment thereof before it enters the inner compartment.

Disposed directly in front of the water 40 intake on the side of the baffle 25 is a deflector 27. Positioned centrally of the drum 15 beneath the convex bottom 16 thereof is a gas heater 28, the burner end 29 thereof being provided with radial jets or openings 45 and the top being closed. This develops a radial flame, so to speak, which is spread out over the convex bottom of the drum so that not only is the entire surface of the drum bottom subjected to the burner flame 50 and heat, but the flame practically envelopes the whole drum and heats the water contained therein very quickly. This is particularly true since the water is distributed throughout the area of the drum by the 55 baffle 25 as it is introduced therein.

The hot water circulating connection 18 extends vertically through the flue 30. The flue in turn is extended centrally and vertically through the tank 5, having an open 60 lower end in communication with a central opening 31 in the top of the dome 6. The products of combustion of the burner 28 will thus pass off through the flue and since the flue is surrounded by the water in the 65 tank, the water derives considerable volume

of heat units from this source. The upper end of the flue is connected to a pipe 32, which in turn may connect with the chimney or other source of disposing of the flue gases and spent products of combustion.

For connecting the flue with the pipe 32 I 70 use an ordinary conventional type of connection. However, in extending the flue through the top 13 of the tank I make a flanged opening in the tank and reduce the diameter of the flue to extend through this flanged opening, so as to provide an abutting annular shoulder, as at 33. The end of the flue and the flange of the opening in the top 13 may be riveted together, as at 34.

The modified conical top 17 of the drum is made with a central opening for the reception of a pipe fitting 35 to which is connected the first one of a series of pipe-like sections which make up the hot water circulating connection 18. These pipe-like sections are joined together by nipples 36 and each one is preferably of casting having either four, three or a pair of internal radially projecting pockets 37. These pockets not only project radially internally of the sections to accommodate water, circulating through the hot water circulating connection but they also provide external heat absorbing projections on the sides of the sections which project radially with respect to the flue. They are preferably arranged in staggered relation, that is to say, the pockets in one section are staggered with 80 relation to the pockets on the adjacent section. 85

The water passing through the hot water circulating connection thus takes a tortuous course and the extra heating surface provided by the projections heats the water to much better advantage. The products of combustion in passing through the flue are deflected by the projections to the side wall of the flue. 90

The top of the hot water circulating connection terminates with the nipple and a short pipe length 38 which extends through an opening in the pipe 32 and is fitted to a T 39. Connected to this T 39 is a hot water service pipe 40, the opposite end of the T 39 105 being equipped with a nipple 41 which projects into the top 13 of the tank to serve as a hot water return. The nipple 41 in this respect is threaded into a flanged and internally threaded connection 42 which is 110 riveted as at 43 to the top 13 of the tank.

With the assembly described cold water will be introduced into the tank through the inlet pipe 44 as the water is drawn off the tank through the service pipe 40. The water is introduced into the drum 15 through the cold water connection 19 and then up through the hot water circulating connection 18 to the T 39 and into the tank 125 through the return 41. 130

Hot water may be drawn from the tank through the service pipe 40 which is connected to the T 39 opposite the return 41.

As a result of the construction of this device the heat is transferred to the water within the tank both directly, through the bottom of the tank and the side wall of the flue pipe and indirectly by the influx into the upper part of the tank of water heated during its passage through the heating drum or disc, and the connection which connects said heating drum with the top of the tank.

The heating drum, which is closest to the source of heat and, therefore, may be termed the primary heating element, communicates with the lower part of the tank, in which the temperature of the water is comparatively low.

20 In order to simplify the connection of the heating drum to the lower part of the tank and to leave the entire lower surface of the same exposed to the heat during operation, the cold water intake pipe connects 25 with the sides of the heating drum instead of the bottom which is usual in heaters of this type.

The cold water intake and the service connection are altogether independent of the 30 circulating means and function independently whether the water is heated or not.

The circulation of water from the lower part of the tank through the heating drum and its several connection pipes to the upper part of the tank is also independent of the withdrawal of water from the tank. It commences as soon as the gas burner is lighted and ceases as soon as the gas is turned off, regardless of whether the water 40 is being drawn from the tank or not.

Obviously anyone skilled in the art may make changes in the arrangement and detailed construction of the assembly described without departing from the spirit of the invention defined by the sub-joined claim and I, therefore, do not wish to be limited to the particular form described.

I claim:

50 A water heater comprising a tank and a combustion chamber thereunder; a flue extending from said combustion chamber vertically through said tank; a heating drum in said combustion chamber, the top of said drum being adjacent and substantially parallel to the bottom of said tank; a circulating pipe connected with the upper part of said drum, extending upwardly through said flue and connected at its upper end to the upper portion of said tank; radiating hollow arms on said pipe at various levels, the arms at each level being staggered with respect to the arms at adjacent levels; a pipe connecting one side of said drum with the lower portion of said tank; said last mentioned pipe extending radially outwardly

through the side wall of said combustion chamber and then upwardly and radially inwardly into the lower portion of said tank to a position adjacent the side of said flue; a vertical partition in said drum starting at a point opposite said last mentioned pipe and extending thence in both directions substantially parallel to the periphery of said drum thereby causing the incoming water to separate into two separate streams; and a burner below said drum, said burner being positioned closely adjacent the bottom of said drum and provided with radial openings projecting flame substantially parallel to the bottom of said drum.

In witness that I claim the foregoing as my invention, I affix my signature this 7th day of June A. D. 1927.
